APPARATUS FOR FLOWING WELLS

Eakin L. Wheless, Shreveport, La.

Application June 17, 1932. Serial No. 617,840

6 Claims. (Cl. 103—233)

This application is a continuation, in part, of my copending application, Serial No. 448,275, filed April 29, 1930, now Patent No. 1,867,639, July 19, 1932, and relates to and includes subject-matter 5 divided out of said copending application.

My invention relates to a method and apparatus for flowing wells and has to do, more particularly, with the siphonic removal of liquid, such as oil or water, from wells in which the liquid is subject to extreme variations in level because of interrupted use or other causes.

Under such conditions, it frequently happens that the wells become so flooded as to be "drowned" and must be pumped by auxiliary 15 equipment before the operation of the conventional siphon or gas lift equipment can be started. It is, accordingly, the primary object of my invention to provide gas lift apparatus which will start flow in flooded wells and the operation of which 20 involves no special technique such as partial withdrawal of the whole apparatus from the well in order to initiate flow.

Another object of my invention is to provide an apparatus and method which is economical in 25 that a minimum of working gas is required, and in which the pressures necessary to initiate flow in flooded wells are not materially greater than those required to maintain flow when the flooded condition has been corrected.

Another object of my invention is to provide 30 a gas lift apparatus for flowing wells which apparatus will initiate flow in a "drowned" well and which will automatically regulate itself to provide a maximum efficiency at the start and as the 35 level of the liquid in the well becomes depressed due to continued withdrawal of liquid therefrom.

Another object of my invention is to provide 40 such an automatic gas lift apparatus for flowing wells which may be furnished with compressed gas from a remote compressor station.

Further objects and objects relating to details 45 and economies of construction and operation will definitely appear from the detailed description to follow. In one instance, I accomplish the objects 50 of my invention by the means set forth in this specification. My invention is clearly defined and pointed out in the appended claims. Structures constituting preferred embodiments of my invention 55 are illustrated in the accompanying drawings forming a part of this specification, in which:

Figure 1 is a vertical view, partly in section, 60 partly in elevation, of apparatus constituting a preferred embodiment of my invention;

Fig. 2 is a vertical sectional view through a por-

tion of the eduction tube extending downwardly through the well casing and, more particularly, of the valve structure providing one of the several ports thereof, said valve being in open position;

Fig. 3 is a similar view showing the valve of Fig. 2 in closed position;

Figs. 4a, 4b and 4c constitute a diagrammatical illustration of the general principles involved in gas lift apparatus of the present type; and

Fig. 5 is a vertical view, partly in section, partly in elevation, of a modified form of apparatus constituting a preferred embodiment of my invention, similar to that illustrated in Fig. 1, and employing the hydraulic lift principle for automatically regulating the operation of the several valves providing ports in the eduction tube.

In lifting oil from wells by the gas lift method, wells are customarily tubed in such a way that the oil may flow to the surface either through the tube or through the annular space between the tube and the well casing. The flow is induced or assisted by forcing compressed air, gas or other working fluid into the well under appropriate pressure and in sufficient volume, either down

through the tubing or through said annular space, depending upon the path selected for the rising oil. The gas so introduced becomes entrained in the oil or liquid and, expanding therein, lightens or aerates the liquid column and, rising, carries the liquid upwardly to the surface. The action of gas lift types of apparatus can best be understood by reference to Figs. 4a, 4b and 4c.

Fig. 4a illustrates an oil well lined with well casing 10 and equipped with an eduction tube 11. During the period in which no oil is removed from the well, the oil rises to what is termed an equilibrium position, with the surface of the oil standing at the elevation S above the lower end of eduction tube 11. This high

"static submergence" of the eduction tube is an expression of the magnitude of the "rock pressure" or maximum expulsive pressure existing within the productive sand. Under these conditions, if compressed air or other working fluid is forced from supply pipe P down into the well between the casing and tubing, and the latter is left open at the top and bottom, while the upper end of casing 10 is sealed by a closure C, the oil

level rises within tube T as the oil surface in the annular space between the tube and casing is depressed. Fig. 4b illustrates the relative positions of these two oil surfaces within and without the tubing when the gas pressure applied is

sufficient to depress the oil surface between those

105

110

two surfaces to the lower end of the tube. At this point, the high pressure gas or working fluid escapes into the lower end of the eduction tube 11 and moves upwardly toward the surface. In 5 doing so, it becomes entrained and dispersed in the oil column in said tube in the form of small bubbles. The viscous condition of the oil and limited cross section of the tube prevent rapid translation or "slippage" of the gas through the 10 oil. As long as this gas, which thus enters the tube, is retained within the oil, the displacement of oil by the volume of gas serves to lower the density of the oil in the tube, further raising the surface of the oil in the tube. Furthermore, 15 as the gas rises through the tube to regions of lower pressure, it expands and its volume is appreciably increased, further lightening and raising the liquid column in the tube. If the volume of the expanded gas added to that of the oil in 20 the tubing is sufficient, the oil-gas column will be extended upwardly until it overflows at the surface, thereby establishing the flow of the oil from the well. These latter stages are illustrated in Fig. 4c.

25 Taking up the matter of pressure conditions existing within the well at the level of the oil productive sand, the effective back pressure on the oil sand opposing the admission of oil, before gas pressure is applied to the well, is equivalent to the static fluid pressure of the oil, below its equilibrium. This, it is assumed, is a pressure substantially equal to the "rock pressure" within the oil sand and there is, therefore, no tendency 30 for additional oil to enter the well. After the gas pressure has been applied and the condition illustrated in Fig. 4b is attained, the pressure on the productive sand will have been increased to an amount determined by the new height reached by the level of the oil surface in eduction tube 11. As gas enters the tube and aerates the oil therein, there will be an additional, but comparatively slight, increase in the pressure developed on the oil sand until the oil overflows from the tube at the surface. The pressure developed during this stage, however, is no longer proportional to the height of the oil column, because the latter has acquired a lower density by reason of the working fluid dispersed therein. Up to this point, there has been a continual increase in pressure on the productive sand which prohibits the admission of additional oil to the well, but as soon as the oil begins to overflow at the surface, the pressure opposing admission of oil to the well from the productive sand begins to 45 diminish. Oil may continue to overflow at the surface only as the result of further aeration of the oil in the tube, the working fluid displacing oil while the density of the oil-gas mixture in the tube becomes lower and lower and the pressure on the productive sand less and less until eventually the pressure on the productive sand becomes less than the original static pressure established under the starting conditions illustrated in Fig. 4a. Under the influence of this reduced 50 pressure, oil may now begin to enter the well, and as the pressure is further diminished, due to more complete aeration of the rising fluid in the eduction tube, the quantity of oil flowing into the well from the productive sand will increase 55 until an equilibrium pressure condition is established.

From the above, it is seen that a higher gas pressure is required at the start than is required for the operation of the gas lift after starting, 60 because when the gas enters the eduction tube

and aerates the oil, the weight of the mixture of oil and gas will be considerably less than the weight of the oil column before aerating, and since the pressure at the bottom of the tube depends upon the weight of the fluid therein, it is, of course, less after the oil in the tube has been aerated. Consequently, gas continues to enter the bottom of the tube at a lower pressure after aeration than before, so the operating pressure, or the pressure required for continuing the flow after flow has once been started, is less than the pressure required for starting. The ratio of the starting pressure to the operating pressure varies in different wells, but frequently, in commercial oil wells, the starting pressure must be two or three times as great as the operating pressure, and, in some cases, it is as much as five times as high. Therefore, in addition to the machinery and equipment necessary for pumping a well with the gas lift, it is also generally necessary to maintain a considerable amount of other machinery and equipment, frequently at a cost of several thousand dollars per well, which is used for starting purposes only and is idle the remainder of the time. From this, it is evident that a great 100 saving can be effected in gas lift operations by a method that will permit starting at a pressure practically equal to or very little in excess of the operating pressure, and, as before pointed out, the primary objects of the present invention are 105 to provide a method possessing this advantage and an efficient apparatus for carrying out such a method.

Stated generally, the method consists in arranging a tube within the well casing, said tube 110 being provided with a series of ports spaced vertically of the well. Working fluid is then supplied either to the tube or casing, at which time all the said ports are open. The oil is gradually depressed as illustrated in Fig. 4a until the 115 working fluid has access to the uppermost port of said tube. The oil is then still further depressed until the working fluid has access to the next lower port and so on, until the working fluid is flowing through some three or four of the 120 uppermost ports and aerating oil within said tube or within said casing, depending upon whether the fluid was originally supplied to the casing or to the tube. After the fluid has gained access to these three or four ports, the uppermost 125 port is closed and the oil level further depressed until another port is uncovered and placed in operation in place of the one closed. All the ports are progressively closed in this fashion, beginning with the uppermost port, a sufficient time 130 interval being permitted to elapse between the closing of successive ports in order to allow the fluid level to be depressed or to recede so as to keep one or more valves uncovered and in operation at all times. The injection of fluid 135 through any opening of the tube will aerate the fluid above and decrease its weight, which will, as soon as the fluid commences to flow out at the inlet point in question, and consequently at any 140 point below it, so that less starting pressure is then required for the injection of fluid at lower points. The starting pressure at each successive lower port, although greater than at those above, is considerably less than if those above had not 145 been in use. The ports are thus closed in order, from the uppermost one to the lowermost, until eventually the entire flow of gas will enter the discharge pipe through the bottom opening, which may be at the bottom of the string of tube, as 150

shown in Figure 1, or some other form of opening at any desired point in the tube. The fluid is thus finally admitted through the bottom opening at a pressure which is very little greater than the pressure necessary to continue operation after starting.

While various forms of apparatus may be utilized for carrying out the method above outlined, the preferred form, illustrated in Figures 1 to 3, 10 is of such construction that the closing of the ports at successively lower points in the well may be accomplished automatically by means operable by the working fluid utilized for flowing the well. In this apparatus, the upper end of casing 10 is sealed by a closure C having a packing gland c for packing material 12, through which the eduction tube 11 extends. At a point immediately below closure C, there is an inlet pipe 13 for supplying working fluid to the interior of 15 casing 10, and at points spaced suitable distances apart longitudinally of the eduction tube 11, there are ports provided in said tube, these ports being preferably constructed as shown in Figs. 2 and 3 and claimed in my copending application, Serial 20 No. 448,275, now Patent No. 1,867,639, July 19, 1932, above referred to. These ports or valves consist of a bushing 14 threaded internally so that it may be secured on one section of the tube and threaded externally for the attachment of 25 what would be termed a port member 15. These port members are in the form of a sleeve having an internal annular shoulder 16 against which the face of the valve member 17 seats to close the port. Valve member 17 is carried by the tube 30 section next above the section on which the bushing 14 is secured. The tube sections are capable of being moved longitudinally of one another to seat and unseat the shoulders 16, 17, but formed on the end face of one of these pipe sections 40 there are one or more lugs 18 that limit the telescoping movement so as to prevent the ends of the two tube sections from coming into contact with one another. In this way, when the two shoulders are separated longitudinally of the 45 tube, there is provided a space 19 between the ends of the adjacent tube sections through which working fluid may flow. These valves or ports are shown in their open position in Fig. 2, and in their closed position in Fig. 3. The threads on 50 the exterior of bushing 14 are preferably straight threads and the bushing and port member 15 are adapted to screw together far enough to tightly compress a gasket 20 between them so as to make a tight joint. The internal diameter of the inner member of this valve arrangement, i. e., that 55 member on which shoulder or valve face 17 is formed, is practically the same as that of the tubing string so as not to interfere with the flow of the aerated liquid. The outside diameter is 60 practically the same as that of the tubing except for an external annular shoulder at one end to 65 cooperate with the annular shoulder 16 on the valve member 15. Preferably, the annular shoulders 16, 17 are concave and convex, respectively, 70 so that they will maintain complete contact even if the tubing string does not hang perfectly straight, due to misalignment or curvature of the well hole. The annular space between the periphery of shoulder 17 and the inner wall of member 75 15 is preferably made larger than the very narrow annular space between the inlet surface 16a of shoulder 16 and the exterior surface of the tubing section above shoulder 17, so that any foreign matter which might pass through this last-mentioned passage will easily pass through

the first-mentioned passage. A port clearance of .010 of an inch between the shoulder 16 and the tubular portion carrying the shoulder 17 has been found most practical from the standpoint of efficiency as well as sufficient to permit the tubing to conform to deviations in the well bore without interference. While the spacing of the valves in the tubing string may vary with various well conditions, a practical working arrangement uniformly satisfactory for use in general 80 air lift operations is as follows:

	Spacing from valve below	Distance from bottom	
Lowest valve.....	20 feet (1 joint).....	20 feet (1 joint).....	90
2nd lowest.....	40 feet (2 joints).....	60 feet (3 joints).....	
3rd lowest.....	60 feet (3 joints).....	120 feet (6 joints).....	
4th lowest.....	80 feet (4 joints).....	200 feet (10 joints).....	
5th lowest.....	100 feet (5 joints).....	300 feet (15 joints).....	
6th lowest.....	120 feet (6 joints).....	420 feet (21 joints).....	
7th lowest.....	140 feet (7 joints).....	560 feet (28 joints).....	
8th lowest.....	160 feet (8 joints).....	720 feet (35 joints).....	
9th lowest.....	180 feet (9 joints).....	900 feet (45 joints).....	
10th lowest.....	200 feet (10 joints).....	1100 feet (55 joints).....	
11th lowest.....	220 feet (11 joints).....	1320 feet (66 joints).....	
12th lowest.....	240 feet (12 joints).....	1560 feet (78 joints).....	
13th lowest.....	260 feet (13 joints).....	1820 feet (91 joints).....	
14th lowest.....	280 feet (14 joints).....	2100 feet (105 joints).....	
15th lowest.....	300 feet (15 joints).....	2400 feet (120 joints).....	100

The present form of valve is exceedingly simple and very rugged. It can be used at any depth; does not require adjustments; and takes up such a comparatively small amount of space 105 that it will not interfere with flow, either in the eduction tube or in the air space between the tube and casing. Moreover, a valve of this type is not apt to become clogged up while in operation.

In flowing a well, the lower end of the tubing string rests upon the bottom of the well or is supported by the well liner or other suitable support and, in starting, all of the valves 16, 17 in the string will be open, due to the weight of the 115 pipe, which telescopes the section ends to open said valves. Gas forced into the annular space between the tubing and the casing under pressure will depress the surface of the liquid in this space until it reaches the uppermost valve, at 120 which point a portion of said gas will flow into and aerate the liquid column within the tube. The annular opening constituting these ports or the spaces between the valve members 16, 17, is made small enough—about .010 of an inch—so 125 that a single valve can accommodate or pass only a small part of the entire amount of gas or working fluid being forced into the well casing. The liquid level in the casing will, under these conditions, continue to be depressed until a number of the valves have been opened to provide ports and the liquid column in the tube is aerated by them all simultaneously. After the first three or four valves have thus come into operation, 130 the uppermost valve may be closed (preferably by means hereinafter described), and the liquid level between the casing and tubing will be further depressed until another valve is uncovered and placed in operation in lieu of the one closed, and by progressively closing all the valves in 140 order, beginning with the uppermost one, the working fluid is forced to still lower valves and is progressively injected into the tube through a series of points successively located at lower positions along the tube. A sufficient time interval 145 should lapse between the closing of successive valves in order that the liquid level may recede ahead of the last closed valve sufficiently to keep several valves uncovered and in operation at all times. The injection of the working fluid 150

through any opening of the tube will aerate the liquid above and decrease its weight, which will, as soon as the liquid commences to flow out of the top of the tube, decrease the liquid pressure 5 at the inlet point in question (and consequently at any point below) so that less starting pressure is then required for the injection of gas at the lower points. Consequently, while the starting pressure at each successive opening will be greater 10 than at the openings above, nevertheless, it will be less than if those openings above had not been used. The valves are closed successively, one after the other, from the top, and those below are successively brought into action until 15 eventually the entire flow of gas will enter the eduction tube through the lowermost opening in the manner shown in Fig. 4c. This bottom opening may be at the bottom of the string of tubing or it may be a joint of perforated pipe or the like. 20 This progressive closing of the valves from the uppermost one downwardly of the well is accomplished by the gradual raising of the tubing string. As the string is slowly raised, it effects the closure of the top valve and then of each 25 succeeding one downwardly of the well. This raising or elevating of the tubing may be effected in various ways, as for example, by means of a piston 21 working in a cylinder 22, mounted on the top of closure C. Piston 21 is connected or 30 attached to tube 11 and a portion of the working fluid from supply pipe 13 is conducted by a pipe 23 to the interior of cylinder 22. A highly restrictive valve 24, preferably a needle valve, is interposed in pipe line 23 in order that the flow 35 of working fluid to cylinder 22 may be regulated in accordance with the rate at which the liquid level in the well is depressed. A reservoir 25 connected by a branch 26 to pipe 23 may also be provided for the reception of a portion of the 40 gas passing valve 24, if it is found that the tubing string must be raised at an exceedingly low rate of speed. After valve 24 has once been set to give the proper flow for the well in question, no further manipulation of that valve, by a well 45 attendant, is necessary and the action of the apparatus may be left entirely automatic. Upon starting up, all of ports 16 in the tubing string will be in their telescoped or open position, and while the major portion of the gas passes downwardly between the casing and tube to depress the liquid and uncover successive ports or valves, an appropriate portion of such gas will, at the 50 same time, flow through pipe 23 and valve 24 into cylinder 22, slowly building up in the cylinder sufficient pressure to raise the piston 21 and the tube. As each valve is closed, the weight or load 55 imposed upon the piston is increased so that additional pressure is required in the cylinder for continuing the elevation of the string, and when the piston has reached the top limit of its travel, the relationship provided by the valve 24 should 60 be such that the liquid level will have reached the bottom opening in the tubing. Ordinarily, the valve 24 would be the only fitting necessary in line 23, but, if desired, other fittings may be used in this line for gauges and the like. Unless 65 a very slow upward movement of the tubing string is desired, reservoir 25 may be dispensed with. If it is desired, either temporarily or permanent- 70 ly, to have the flow of liquid from a point higher in the well than at the lowermost opening, the length of the travel of the piston in cylinder 22 may be regulated by suitable means, such as ad- 75 justable stops 27. In this way, the back pressure on the productive oil sand during operation may

be readily regulated. The opening of the needle valve 24 need not be changed when the gas is cut off to shut down the well, as the gas in the cylinder may flow slowly out of the cylinder through the valve, allowing the tubing to settle down gradually. Under such conditions, the tubing will return to its original position in a comparatively short time, with the several valves telescoped or open and ready for the well to be started up again. From the foregoing, it will be seen that this apparatus is automatic in that, once adjusted to the particular well, it does not require the presence of anyone at the well to attend to it, even when the gas is being furnished from a distant compressing station. 80

Under some conditions, it may be desirable to use a counterweight 28 connected by a flexible member 29, running over pulleys 30, with the upper end of the tubing string. At the pressures ordinarily prevailing in gas lift operations, the raising of the tubing will not require very large cylinders. For instance, a cylinder of eight-inch diameter and a pressure of three hundred pounds per square inch is sufficient to lift about four thousand feet of ordinary two-inch tubing having a weight of approximately fifteen thousand pounds. 90

While I have described the present invention as employed with a well casing into which the eduction tube through which the well liquid is forced to the surface is disposed, it is obvious that the procedure may be reversed, employing the well casing as the eduction duct and the inserted tube as the duct for introducing the compressed working gas. Likewise other designs 105 of valves peculiarly adapted for either one or the other mode of liquid eduction may be employed. Two forms of valves are disclosed and claimed in my prior application Serial No. 448,275, now Patent No. 1,867,639, July 19, 1932, 110 to which reference has previously been made.

In Fig. 5 of the drawings I have shown a somewhat modified form of tubing string elevating apparatus for appropriately governing the actuation of the several valves in accordance with 115 pumping progress. As in the apparatus shown in Fig. 1 there is provided a piston 81 working in a cylinder 82 mounted on the top of a well casing closure or head C. Piston 81 is coupled to the eduction tube 11 and may be limited in its upward extent of movement by threaded stops 27. A compressed gas duct 13 is threaded into the closure C and communicates with and supplies the well casing 10. For the purpose of providing a lifting effort upon the under side of the 120 piston 81, there is provided a tank 85 for oil, glycerine or other suitable hydraulic lift fluid, the level of which is shown at x. A small duct 83 for compressed gas leads from the well casing cap C and, controlled by a highly restrictive valve 125 84, provides an extremely slow discharge of gas from the well casing head into the air space of the tank 85. An oil supply duct 86 leads from the sump 85a of the tank into the cylinder 82 and, as gas pressure is slowly being built up in the 130 tank 85 by the gas passing through the highly restrictive valve 84, oil is slowly displaced from the tank 85 into the pipe 86, gradually filling the cylinder 82 and raising the piston 81. By means of appropriate adjustment of the valve 84, the 135 piston movement may be timed to effect tube elevation in accordance with the characteristics of the well, which in most instances are fairly uniform from day to day during the active life of the well. This apparatus, once adjusted, may, 140

like that shown in Fig. 1, therefore be employed as an automatic system dependent solely upon the supply of compressed gas, even though from a remote source.

- 5 While the apparatus and method constituting the present invention have been described as being used essentially for starting gas lift wells it will be appreciated that the same apparatus and the same method may also be utilized for 10 what is termed the deliquefaction of gas wells. One of the major problems in the operation of natural gas wells is the removal of liquids such as oil or salt water which continue to flow or seep into the bottom of the well from the gas sand along with the gas. If allowed to accumulate this liquid will eventually fill the well to a point where the flow of gas from the sand will cease and the well become dead. This point will be reached when the fluid pressure upon the 15 producing sand, due to the weight of the accumulated column of liquid in the well, approximately equals or exceeds the gas pressure in the same. The rate of gas production will, of course, decline in proportion to this pressure of the liquid if the 20 liquid level rises in the well. It will, also, be understood that the rate of accumulation of the liquid in various wells varies with each particular well and the conditions of operation thereof. For instance, if a high back pressure is maintained upon the sand the inflow of liquid will be 25 less, and when the back pressure is lower, by increasing the rate of gas discharge from the well, the liquid will flow faster and, therefore, accumulate more rapidly. Ordinarily, this 30 accumulated liquid is removed by means of a siphon line constituted by a string of comparatively small pipe run from the top of the well to the level from which it is desired to remove the accumulated liquid, and open at the top to permit free 35 discharge of the gas to the atmosphere. If a small pipe is used the flow of gas will be kept to a minimum, but on account of internal friction the velocity may not be great enough to get the greatest efficiency in the lifting of the entrained 40 liquid particles. The size of the pipe must, therefore, be determined by the conditions of the well, depth, pressure, amount of fluid to be removed, etc., and a pipe chosen that will remove the desired amount of fluid with the least expenditure of gas. The simplest form of siphon 45 contains no other openings than those at the two ends, the gas entering at the lower end and discharging with the liquid at the upper end.
- When the fluid level rises as high as the lower 50 end of the siphon, gas flowing through the siphon will pick up small particles of the liquid and carry them up and out in much the same way that particles of moisture are carried in wet stream, that is, the liquid is in the disperse phase 55 and supported in and raised by the gas by virtue of its velocity. If the water should enter the well faster than it is removed the liquid level will, of course, build up to the point at which the siphon will become inoperative and the liquid will accumulate still faster thereafter until the well is 60 dead. This frequently happens when the back pressure in the well is lowered by withdrawing the gas at an unusually high rate, during peak loads or other unusual conditions. The remedy 65 usually is to raise the siphon from above until the lower end is near enough the surface of the fluid to permit the siphon to operate and then to lower it again after enough water has been removed to permit it to operate at a lower position. This, of course, is a slow, troublesome and 70 expensive process, since the siphon line is packed off at the top of the well to prevent leakage around it, and these packing members must be removed to permit the passage of pipe couplings. Also, equipment for the raising and lowering of the tubing must be procured, or kept on hand for the purpose. If the well is not entirely dead it may be deliquefied in this way with its own gas; but if its own flow has practically stopped, gas must be introduced into it from some other source. 75
- There are other varieties of siphons in general use following the general principle of admitting water into the siphon at the lower end and the gas at points somewhat higher, the gas openings being small enough to maintain the necessary 80 pressure differential to cause a column of fluid to stand in the siphon and the lowest gas inlet being near enough the bottom of the siphon to cause the gas entering through it to pass through the water column. Additional openings are located somewhat higher so that if the fluid level rises and seals off the lower opening, gas will still be admitted to the siphon line and pass through the water column therein. The utility 85 of these higher openings under ordinary conditions, that is, when the lowest opening is in operation seems to be in dispute, but it would seem that they would really be worse than useless until those openings below were closed, because the gas entering through the higher openings would 90 not pass through the solid water column to nebulize it but instead is passed above the water, not only not doing any useful work but increasing the back pressure inside the lower end of the siphon and thereby decreasing the velocity and rate of 95 expansion of the gas at the lower end, and, therefore, decreasing its ability to nebulize and pick up water. 100
- In view of this the apparatus and the method of the present invention may be advantageously 105 used for the siphoning or deliquefying of gas wells. For instance, the tube 11 with the multiplicity of longitudinally spaced ports may be lowered in the well with its lower end slightly off the bottom so that all the valves may be closed, under which 110 circumstances the tube will serve as a siphon to elevate liquid entering its lower end. If, however, the liquid level in the well rises so that the siphon ceases to operate, the string of tubing 11 is lowered, opening successively from the bottom 115 upwardly as many of the valves in the string as may be necessary to again start the siphon in action, it being understood that the gas produced in the well will enter the opened ports to produce the siphon action. When enough water has been 120 thus removed, the siphon string or the string of tubing 11 is again raised, closing one or more of the valves or ports and diverting the gas to a lower point of entry and so on until the tubing is 125 finally raised to its original position. In other 130 words, where the present apparatus is used as a siphon instead of air or gas under pressure being supplied to the well, the natural gas, commonly under natural pressure, is utilized. When using the present apparatus and method for removing water from drowned gas wells, it is preferable to arrange the valve spacing in the inverse order, that is, with a spacing of from 40 to 60 135 feet at the bottom, graduating upwardly to a spacing of approximately 20 feet at and above 140 the high water level. A practical working arrangement for use in a siphon system requiring a tubing string having a fifteen valve ported portion of 600 feet is as follows: 60 foot spacing (3 joints) 145 between each of the five lowermost valves. 40 150

foot spacing (2 joints) between each of the five intermediate valves, and 20 foot spacing (1 joint) between each of the five uppermost valves. This difference in spacing order over that found most expedient in the air lift pumping of oil wells is due primarily to the fact that the natural pressure of the gas will ordinarily increase as the well is being drained. Moreover, flooding troubles requiring the present system most commonly occur 10 in old gas wells in which production and pressure has declined due to partial exhaustion.

I am aware that the form and mode of operation of my preferred apparatus may be varied considerably without departing from the scope of 15 the invention. For example, instead of relying upon the needle valve 84 in the gas line 83 of my apparatus illustrated in Fig. 5 as the piston movement-determining element, I may employ the valve 87 in the oil supply duct 86 for the same 20 purpose. Due to the greater restriction capable of attainment upon a liquid, the use of a highly restrictive needle valve in the duct 86 is not so essential, though, under some circumstances, it may be desirable.

25 What I claim is:

1. The method of initiating and maintaining flow from a well in which the liquid stands at a level higher than that normal to the operation 30 of the well, which comprises extending an open-ended liquid eduction tube into the well to the level to which the liquid in the well is to be lowered, maintaining gas under pressure in the well space about said eduction tube and upon the surface of the liquid in said space to depress 35 the level of said liquid therein and raise the level of the liquid in said eduction tube providing a static column of liquid in said tube above the depressed level of the liquid in said well space, simultaneously injecting gas under pressure from 40 said well space into said liquid column in said tube at a plurality of vertically spaced points, permitting said injected gas to rise through, expand, and aerate said liquid column, reducing the density thereof to such an extent as to enable the 45 pressure in said well space to so raise said aerated liquid in said tube as to cause flow therefrom, continuing the injection of said gas from said well space into said tube at said vertically spaced points to lower the liquid level in said well space, 50 and progressively lowering the injection points as the level of the liquid in the well space is lowered.

2. The method of initiating and maintaining flow from a well in which the liquid stands at a level higher than that normal to the operation 55 of the well, which comprises extending a pair of open-ended tubular members into the well bore to the level to which the liquid in the well is to be lowered, one of said tubular members being disposed within the other, thus providing distinct 60 inner and outer ducts, maintaining gas under pressure in one of said ducts, thereby depressing the level of the liquid therein and raising the level of the liquid in the other duct simultaneously, injecting small streams of the gas from the gas-charged duct into the column of liquid in the other duct at a plurality of vertically spaced points to aerate said liquid column and so decrease its density as to cause the upward pressure upon the bottom thereof due to the greater weight 70 of the liquid in said gas-charged duct and the gas pressure thereon to effect discharge of the aerated liquid from its duct, continuing the injection of said gas into said flowing column of liquid to reduce the amount of liquid in said well, and progressively lowering the points of injection as the 75

level of the liquid in the gas-charged duct is lowered.

3. A semi-automatic apparatus for intermittently flowing a well subject to flooding when not continually pumped, comprising a well casing, a liquid eduction tube extending downwardly within said casing to the level to which the well is to be pumped, means for providing gas under pressure in the space between the well casing and said tube, a plurality of telescoping valves disposed at vertically spaced positions along said tube, associated therewith to provide vertically spaced gas injection ports at said positions, closed when said tube is suspended and successively openable in upward order by progressively supporting more and more of the weight of the tube upon its lower end, a cylinder, a piston in said cylinder and coupled to said tube to raise and lower the same and control the adjustment of said valves so that gas is injected through several valves simultaneously, a cylinder charging duct communicating with said gas space between said well casing and said tube, and a restriction in said duct automatically regulating the rate of cylinder charging to provide valve actuation by 100 said piston and lowering of the gas injection points in conformity with the rate of depression of liquid level in said well casing.

4. A semi-automatic apparatus for intermittently flowing a well subject to flooding when not continually pumped, comprising a well casing, a liquid eduction tube extending downwardly within said casing to the level to which the well is to be pumped, means for providing gas under pressure in the space between the well casing and 110 said tube, a plurality of telescoping valves disposed at vertically spaced positions along said tube, associated therewith to provide vertically spaced gas injection ports at said positions, closed when said tube is suspended and successively openable in upward order by progressively supporting more and more of the weight of the tube upon its lower end, a cylinder, a piston in said cylinder and coupled to said tube to raise and lower the same and control the adjustment of 120 said valves so that gas is injected through several valves simultaneously, a cylinder charging duct communicating with said gas space between said well casing and said tube, and an adjustable, highly restrictive valve in said duct automatically 125 regulating the rate of cylinder charging to provide valve actuation by said piston and lowering of the gas injection points in conformity with the rate of depression of liquid level in said well casing.

5. A semi-automatic apparatus for intermittently flowing a well subject to flooding when not continually pumped, comprising a well casing, a liquid eduction tube extending downwardly within said casing to the level to which the well is to 135 be pumped, means for providing gas under pressure in the space between the well casing and said tube, a plurality of telescoping valves disposed at vertically spaced positions along said tube, associated therewith to provide vertically 140 spaced gas injection ports at said positions, closed when said tube is suspended and successively openable in upward order by progressively supporting more and more of the weight of the tube upon its lower end, a cylinder, a piston in said 145 cylinder and coupled to said tube to raise and lower the same and control the adjustment of said valves so that gas is injected through several valves simultaneously, a cylinder charging duct communicating with said gas space between said 150

- well casing and said tube, a flow-restricting valve in said duct, and a gas reservoir having connection with the portion of said duct intermediate said valve and cylinder, said cylinder, flow-restricting valve and reservoir being so proportioned with respect to the rate of flow of liquid and gas into and out of said well and the weight of the eduction tube as to provide valve actuation by said piston in conformity with the rate of depression of liquid level in said well casing.
6. A semi-automatic apparatus for intermittently flowing a well subject to flooding when not continually pumped, comprising a well casing, a liquid eduction tube extending downwardly within said casing to the level to which the well is to be pumped, means for providing gas under pressure in the space between the well casing and said tube, a plurality of telescoping valves disposed at vertically spaced positions along said tube, associated therewith to provide gas injection ports at said positions, closed when said tube is suspended and successively openable in upward order by progressively supporting more and more of the weight of the tube upon its lower end, and oil lift means for effecting raising of said eduction tube to provide accurate actuation of said valves in accordance with draining of the well and depression of oil level in said well casing, said means comprising a cylinder, a piston disposed therein and coupled to said eduction tube, a reservoir for a quantity of oil, a cylinder charging oil duct communicating with said reservoir, a reservoir charging gas duct communicating with said well casing, and a highly restrictive valve regulating displacement of oil from said reservoir into said cylinder.
